(57) **CLAIM**

The ornamental design for a mobile robot platform as shown and described.

DESCRIPTION

FIG. 1 is a perspective view of the mobile robot platform according to the present invention.

FIG. 2 is a front view of the mobile robot platform of FIG. 1.

FIG. 3 is a rear view of the mobile robot platform of FIG. 1.

FIG. 4 is a left side view of the mobile robot platform of FIG. 1.

FIG. 5 is a right side view of the mobile robot platform of FIG. 1.

FIG. 6 is a top view of the mobile robot platform of FIG. 1; and,

FIG. 7 is a bottom view of the mobile robot platform of FIG. 1.

The broken lines in the drawings depict portions of the mobile robot platform and form no part of the claimed design.
